UNITED STATES PATENT OFFICE

114,230

DESIGN FOR A DIRECTION SIGNAL FOR AUTOMOBILES

Willard L. Morrison, Lake Forest, Ill.

Application January 7, 1937, Serial No. 66,931

Term of patent 3½ years

To all whom it may concern:

Be it known that I, Willard L. Morrison, a citizen of the United States, residing at Lake Forest, in the county of Lake and State of Illinois, have invented a new, original, and ornamental Design for a Direction Signal for Automobiles, of which the following is a specification, reference being had to the accompanying drawing, forming part thereof.

Fig. 1 is a top plan view of the direction signal showing my new design;

Fig. 2 is a rear elevational view; and

Fig. 3 is a side elevational view thereof.

I claim:

The ornamental design for a direction signal for automobiles, substantially as shown.

WILLARD L. MORRISON.
